HORIZONTALLY DIVIDED LOCKER

Marvin D. Rosenberg, Glencoe, Ill., assignor to Convenience Locker Corp., Chicago, Ill.

Filed Nov. 6, 1970, Ser. No. 25,856

Term of patent 14 years

Int. Cl. D6—04

U.S. Cl. D6—168

FIG. 1 is a front perspective view showing my new design for a horizontally divided locker, the unseen right side of the locker being substantially identical to the shown left side and the unshown rear side and bottom forming no part of my design;

FIG. 2 is a front perspective view of a first modified form of my new design for a horizontally divided locker;

FIG. 3 is a second modified form of my new design; and

FIG. 4 is a third modified form of my new design.

I claim:

The ornamental design for a horizontally divided locker, substantially as shown and described.
